Filed Dec. 13, 1962, Ser. No. 72,829

Term of patent 14 years

(Cl. D35—3)

FIG. 1.

FIG. 2.

FIG. 3.

FIG. 5.

The dominant features of my design reside in those portions shown in full lines.

I claim:

The ornamental design for a combination planter box and memo board, substantially as shown and described.
